UNITED STATES PATENT OFFICE

HENRY E. LEPPERT, OF NEW BRITAIN, CONNECTICUT, ASSIGNOR TO THE TRUMBULL ELECTRIC MANUFACTURING COMPANY, OF PLAINVILLE, CONNECTICUT

PANEL-BOARD SWITCH

Application filed January 18, 1928. Serial No. 247,611.

This invention relates generally to snap switches but more particularly to quick-make and quick-break switches adapted for panel board use.

5 What is commonly known as a panel board is the combination, in a single construction, of bus bars, switches, fuses, wire connectors, etc. for the purpose of separately controlling branch circuits. The construction is usually 10 mounted in a suitable enclosing cabinet and is preferably provided with insulating means whereby the operator is protected from accidental contact with live parts.

Panel boards are usually installed in office 15 buildings, apartment houses or other buildings having a number of tenants and are so arranged that each tenant may control his own individual circuit. The average tenant has no electrical knowledge beyond how to 20 operate the switch or replace a blown fuse, therefore it is of prime importance that all elements of chance or danger be eliminated in the construction of a panel board and that the construction be sturdy and dependable.

25 Standard fuses are made to standard dimensions and grouped according to capacity as, for instance, 0 to 30 amp. 125 v., 0 to 30 amp. 250 v., 31 to 60 amp. 250 v., etc., and in each group the outside dimensions are identical, thus, in the first group for example, the fuses are of the plug type and all the casing 30 dimensions are identical whether they enclose a one ampere fuse, a thirty ampere fuse or one of any other rating between the limits.

35 Each branch circuit is provided with a receptacle or clips for receiving standard fuses of either the plug or cartridge type and it is due to this fact that the requirements of a suitable operating switch are peculiar. The 40 underwriters will permit only a relatively small load to be operated from each branch circuit yet each circuit is provided with either a receptacle or clips which will receive fuses of full thirty amperes capacity and it naturally follows that the branch switches must be 45 able to break the full thirty ampere load in case the circuit has been overfused. It further follows that, in order to secure the underwriters' approval, the switch must first 50 undergo the regular tests which include the

successful operation under a load of thirty-seven and one-half amperes at 250 volts.

From the foregoing it will be clear that a panel board switch must be of a very substantial and dependable construction and must be able to meet severe service conditions and yet it is very desirable that the switch be comparatively very small.

Because of the many difficulties in providing a suitable and practical switch, it has been 60 common practice to use switches of the knife blade type but this had the serious objection that practically all of the live parts were exposed. It is desirable that the switch be of the toggle type but such switches of this class 65 as have been placed upon the market have been either too large and cumbersome or have failed to meet the severe conditions of usage.

Applicant's main purpose has been to provide a switch having all of the desirable requirements and which will meet with the full 70 approval of the underwriters and yet be no larger in size than an ordinary ten ampere switch.

Some of the novel features in the preferred 75 form of my construction are as follows: All of the switch parts except the operating handle, the spring and the rivets are made of die-blanked sheet stock which insures absolute duplication and the parts are permanently assembled upon the insulating base as 80 a unit and entirely without the use of screws. The rocker plate is a flat blank having shoulders which fulcrum on cooperating shoulders on the frame, and portions at both sides of the fulcrum shoulder which cooperate with angular shoulders on the frame to form stops for the plate in both of its positions and at both sides of the fulcrum shoulder. A central opening in the plate permits the passage 85 of the operating spring when passing the center line of its operating movement. A bridge portion cooperates with cam shoulders on the operating plate carried by the handle to form a simple "knock-off" for positively 90 starting the operating movement of the rocker plate. This bridge portion also greatly strengthens the operating plate and adapts it for heavy duty service. A spring 95 positioning lug securely retains one end of 100

the operating spring in position without the use of washers and allows the spring to rock upon its bearing in its operating movement. It will be particularly noted that there are 5 no bends in this plate. With the exception of riveting the switch blades in position on the extending lugs, the plate is finished and ready for use as it comes from the blanking dies.

10 The operating lever or handle is provided with a flat sheet metal operating plate having cam shoulders for engagement with the bridge portion of the rocker plate for easily yet positively starting the operating movement of the rocker plate. The operating plate is further provided with an extension having a slot the bottom of which forms a bearing for the turned in end of the operating spring without the use of washers or additional fastening means.

15 The operating spring is of the compression type, one of its ends being open but bent or ground off so that the plane of the end coil is at right angles to the axis of the spring so as to allow it to fit over and rest perpendicularly upon a positioning lug carried by the rocker plate and the other end having the end of the coil bent so as to cross the center line of the coil and thus form a pivot bearing for the spring in the slot of the operating plate. No washers or other extra parts are required to position or guide the spring and it may easily be attached or detached by merely compressing the coils. This 25 method allows for the maximum length of spring which is important because the space is limited and it also allows for a perfectly free rocking movement of the spring at its bearing points during its operating movement.

20 The stationary and movable contacts are preferably made of copper and compressed at their contact making heads as per my former Patent No. 1,552,993 because it is found that such contacts will carry a much 30 greater current than other forms of contacts and with comparatively very little heating effect.

25 It is becoming general practice to fuse only one side of the circuit in a panel board branch circuit and full advantage has been taken of that fact by using two blades and two pairs of stationary contacts or terminals, each pair being formed from the same blank and being, in effect, a double terminal. The blades are arranged to make or break the circuit simultaneously, the circuit flow being divided between them and this construction makes it possible to properly carry the current 35 through a switch of comparatively minute dimensions.

The switch is provided with an insulating cover having slots and barriers so arranged as to support the free ends of the terminals 40 and to prevent arcing of the current to adja-

cent parts of the switch or to another adjacent switch or other metal parts.

As the switch blades move away from the terminals, they are housed in narrow slots in the insulating cover and the slots tend to 70 greatly minimize if not entirely dissipate the arc should one start to form.

This insulating cover may be secured to the switch proper by means of screws or other fastening means if so desired but, as shown 75 in the drawings, it does not require any fastening means because it is held in place by the outside cover plate.

It may be further noted that the frame of the switch is open at one side and also 80 at the bottom to permit the rocker plate to be located upon its bearings in the sides of the frame and that the rocker plate is retained in operative position by the force of the compression spring.

85 Fig. 1 is a front view of a panel board cabinet or casing with switches embodying my invention but omitting the cover or door and showing the place for the insertion of two switches.

90 Fig. 2 is a vertical sectional view of the casing or panel board box showing the ends of the switch supporting units or panel sections.

95 Fig. 3 is a horizontal sectional view of the casing showing a panel section.

Fig. 4 is a longitudinal sectional view and side elevation of a switch embodying my invention.

100 Fig. 5 is a transverse sectional view of the same on the line 5-5 of Fig. 4.

Fig. 6 is a cross section and plan omitting the cover plate.

105 Fig. 7 is an end view of a switch unit omitting the insulating housing.

Fig. 8 is a side view and section of one of the switch units showing the parts in the open circuit position.

110 Fig. 9 is a similar view showing the parts in the closed circuit position.

Fig. 10 is a similar view showing the spring compressed and about to close the circuit.

115 Fig. 11 is a bottom view of one of the switch units.

Fig. 12 is a perspective view showing a modification.

Fig. 13 is an exploded perspective view of the various parts of a switch unit.

120 Fig. 14 is a detail sectional view of the handle and showing the operating plate.

The cabinet, box or receptacle 15, in which the parts are mounted, has a face plate 16 and a door 17 of any suitable character.

125 Each section of the panel consists of a support or base 18 and is preferably provided with two switch units including fuse sockets of any suitable type. Bus bars 19 are provided behind the panel sections and a bracket 20 is secured to each bus bar for connection with one of the switch terminals. The other 130

switch terminal 21 is connected to the load terminal 22 thru a suitable protecting fuse or socket 23. Each pair of switches 24 has a common cover plate 25.

5 Each switch unit has a base plate 26 formed of insulating material which serves to support all the parts of the switch proper.

10 The stationary switch contacts are blanked from sheet metal and preferably each member consists of a base or foot 27 which is adapted to be riveted to the base 26, upright posts 28 connected by a cross bar 29, and contact arms 30. Thus the two posts are tied together as a unit and reenforce each other.

15 The switch frame is preferably formed of sheet metal with side plates 31 which have lugs 32 adapted to be riveted to the insulating base 26. These side plates are preferably connected by integral cross pieces 33 which serve as stops for the oscillating operating member. The operating member consists of a handle 34 of insulating material and a flat C-shaped operating plate having two arms 35 and 36 and is pivoted on pin 34.

20 25 The movable switch members 37, preferably in pairs, are carried by a plate 38 which is detachably and pivotally supported in the frame. This plate has shoulders 39 which rest in the V-shaped notches 40 of the frame. The notches 40 are rounded at the bottom to form a pivot bearing for the rocker plate 38. The spring 41 has one end seated on the lug 42 in the bottom of the plate 38 and at the other end the coil is bent so as to form 30 a cross piece 43 which is hooked into the slot 44 at the rear end of the arm 36 to form a bearing for that end of the spring. This method of pivotally mounting the spring obviates the necessity for any washers or 35 guiding means and allows for the complete operating movement of the spring without distortions or strains, in fact the operating pressure is exerted in a straight line between the bearing points of the spring at all times.

40 45 In the open circuit position shown in Fig. 8, this spring 41, pressing against the lug 42 and the arm 36, holds the parts so that the shoulder 45 abuts against the under side of cross piece 33 of the frame. In this position the sides 46 of the plate 38 are pressed against the side 47 of the V-shaped notch 40. At the same time the side 48 of the plate 38 is pressed against the shoulder 49 so as to afford an evenly balanced support for the 45 plate 38. In the closed circuit position of Fig. 9 the spring holds the parts in position with the shoulder 50 pressing against the cross piece 33 at the left. The sides 48 of the plate 38 are now pressed against the shoulder 51 while the sides 46 are pressed against the shoulder 52.

In order to break the circuit it is simply necessary to move the operating lever 34 from one position to the other.

50 55 Fig. 10 shows the beginning of this move.

ment. It will be seen that the arm 36 engages the top of the cross bar of the plate 38 so as to forcibly start the tilting of the plate 38 before the arm 36 carries the cross piece 43 of the spring 41 past the center line. The switch, therefore, does not rely upon the spring alone to start the snap action altho as soon as the snap action has started it is obvious that the movement cannot be interfered with by the operator.

75 It will be obvious that in moving from the open circuit to the closed circuit position the arms 35 will coat with the plate 38 in the same manner as above described with respect to the arm 36.

80 Each of the movable switch contacts is preferably made up as above described of two members 37 which are suitably secured to but insulated from the oscillating or tilting carrier plate 38. The method of attachment is clearly shown in Fig. 13, the plate 38 being provided with two small pin-like projections or lugs 53, adapted to pass thru washer plates 54 and 55 and be riveted over on the outer ends. Insulating washers 56 and 57 are interposed 85 next to the contact plates 37 and insulating bushings 58 mounted on the pins 53 extend thru the plates 56, 37 and 57 to insulate the contact members 57 from the carrier plate 38.

90 95 For convenience in installing the switch unit the feet 27 and 27' may be provided with notches such as 59 and 60 adapted to be detachably slipped under the heads of the attaching screws.

100 Altho the switch above described has great utility for the various uses for which snap switches are commonly employed, I have found it possible to greatly increase the stability and carrying capacity of the switch by a peculiar form of housing illustrated in Figs. 4 to 7. This housing 62 may be of any suitable insulating material designed to enclose the switch contacts. This housing is provided with a projection 63 which fits between the posts 28 and serves to position and support them.

105 110 The flanges 64 embrace the sides of the frame 31 and form narrow slots 65 for the contact arms 30. This provides very close quarters for the movable switch members 37 and serves to snuff out any arc which tends to form. Flanges 66 are designed to fit close to the shanks of the contact members 30 so as to definitely prevent displacing them from their proper positions. This housing 62 may 115 conveniently be held in place by the cover plate 25 and the screws 67 which pass thru the cover plate and are seated in the lugs 68 of the switch frame.

120 125 In Fig. 12 I have shown a modified form of housing 70 which combines the function of the cover plate 25 and the housing 62 as previously described. Such a construction is particularly adapted for use with single switch units.

While some of the foregoing details may seem of little importance in themselves, yet the combination of the same in a single construction has resulted in a switch which is admirably adapted for its purpose and one which will properly control an electrical circuit of far greater capacity than could reasonably be expected of a switch of such comparatively small dimensions. In fact in accurately calibrated tests, it has been found that a switch of this design and of approximately the same size as an ordinary ten ampere switch will safely and continuously operate on a current of 75 amperes at 250 volts.

15 While the foregoing describes my construction more particularly as a panel board switch, it is obvious that the general ideas involved may be employed in the construction of a single blade switch, a double pole switch 20 or, in fact, in any of the usual forms as are usually furnished by the regular trade.

I claim:

1. A snap switch including an insulating base, a switch contact member secured to said base, said contact member comprising a single stamping having a foot secured to said base and two projecting posts each post having a contact tip and a cross bar connecting said posts intermediate said tips and said foot.

30 2. A snap switch including an insulating base, a switch contact member secured to each end of said base, each contact member comprising a single stamping having a foot secured to said base and two projecting posts 35 terminating in contact tips and a cross bar connecting said posts intermediate said tips and said foot.

3. A switch member comprising a flat plate having a central perforation and having a spring positioning lug at one end of said perforation and a starting abutment at the other end of said perforation, bearing shoulders at the inner edges of the perforation and lugs projecting laterally from the outer edges 45 of the plate and contact arms riveted on said lugs, said starting abutment extending entirely across the end of said plate and connecting the side portions thereof to re-inforce said plate.

50 4. A switch including a frame having open-sided bearings, a rocker plate having bearings extending toward each other and pivotally supported in said bearings of said frame and having a spring positioning lug 55 at one end and a cross bar at the other end, said rocker plate having a central opening with closed sides and ends, an oscillating operating member supported in said frame and having two arms adapted to engage said cross bar for starting said plate, one arm being adapted to pass through said plate, and a compression spring interposed between said lug and one of said arms.

5. A switch including a frame having 65 bearings, a flat rocker plate pivotally sup-

ported in said bearings and having a lug at its inner end and a central closed sided opening, an oscillating operating member supported in said frame and having stop shoulders to engage said frame and having an arm adapted to pass through said rocker plate, and a compression spring interposed between said lug and said arm.

6. A panel board switch including a base, stationary terminals supported on said base and having integral contact tip portions projecting from said base, a switch frame supported on said base, a movable switch member pivotally mounted on said frame for engagement with said contact tips and a readily removable insulating housing for covering and for partially surrounding said stationary terminals and said housing having grooves for receiving and partially surrounding a portion of said stationary terminals to insulate said frame from the contact making portions of said terminals and said movable blade.

7. A panel board switch including a base, stationary terminals supported on said base and having contact tip portions projecting from said base, a switch frame supported on said base, a movable switch member mounted on said frame for engagement with the contact tip portions of said terminals and a readily removable housing for covering said contact tip portions and for partially surrounding said stationary terminals, said housing having grooves for receiving and partially surrounding said stationary terminals 100 to insulate said frame from the contact making portions of said terminals and said movable blades, the said housing having recesses to receive portions of said terminals at points adjacent to the respective contact tip portions for maintaining said contact tip portions in operable position.

8. A panel board switch including a base, switch terminals supported at opposite sides of each end of said base and having contact tips projecting from said base, a switch frame supported on said base, a movable switch blade mounted on said frame for engagement with said contact tips and a readily removable insulating housing for covering and for partially surrounding said switch terminals, said housing having barriers adapted to be interposed between the said frame and the contact making portions of the respective switch members, a cover plate 115 for said housing and switch operating means accessible through said cover plate.

9. A panel board switch including a base, oppositely disposed terminals supported on said base and having contact tips projecting from said base, a switch frame supported on said base, movable switch blades mounted on said frame and having contact tips, a readily removable housing for covering and for partially surrounding said 125

switch terminals, said housing having integral barriers adapted to be interposed between the respective contact tips and said frame, a cover plate for said housing and 5 switch operating means operable through said cover plate and said insulating housing having positioning recesses to receive a portion of said terminals at a point adjacent to the respective contact tips.
